UNITED STATES PATENT OFFICE.

JOHN J. SWEENEY, OF BROOKLYN, NEW YORK.

DESIGN FOR THE ORNAMENTATION OF METAL.

SPECIFICATION forming part of Design No. 21,437, dated March 29, 1892.

Application filed February 27, 1892. Serial No. 423,088. Term of patent 14 years.

To all whom it may concern:

Be it known that I, JOHN J. SWEENEY, a citizen of the United States, residing in Brooklyn, Kings county, New York, have invented and produced a new and original Design for the Ornamentation of Metal, of which the following is a full, clear, and exact description, reference being had to the accompanying drawings, and to the letters of reference marked thereon.

My design has relation to the ornamentation of sheet metal; and it consists of representations of raised flowers with their stems and leaves, bee-hives, and bees in groups arranged in regularly-recurring order upon the surface, the intervening spaces or ground between said representations being covered with numerous fine raised and rounded points uniformly disposed at about equal distances apart, substantially as shown in the drawings.

In the drawings, Figure 1 is a plan or top view of a fragment of sheet metal ornamented with my design, and Fig. 2 is a cross-section of the sheet thus ornamented.

A is a piece of sheet metal, which may be of any width and length. Upon the surface of this sheet are representations or patterns in relief of leaves and flowers *aa*, arranged in recurring but connected groups; representations or patterns of bee-hives *bb*, of conical form, also arranged in recurring order and uniformly distributed, and representations of

bees *c c*, arranged about or adjacent to the bee-hives *b*. The groups comprising representations of the bee-hives and bees are distributed at regular intervals over the surface, each being surrounded by the connected groups of representations of flowers and leaves. The spaces between the groups are covered with numerous small raised points or *d*, of substantially uniform size, which have the effect of a matted surface on the metal and serve to break up and modify the reflection of light from the metal surface.

45

Having thus described my design, I claim— The herein-described design for the ornamentation of sheet metal, which consists of the connected and recurring groups of raised patterns of flowers and leaves *a*, the recurring groups of raised patterns of bee-hives *b* and bees *c*, the latter groups being each surrounded by the connected patterns of flowers, and the raised dots or points *d*, uniformly distributed over the ground between the said groups, as shown.

50

In witness whereof I have hereunto signed my name in the presence of two subscribing witnesses.

JOHN J. SWEENEY.

Witnesses:

HENRY CONNETT,
JOHN D. CAPLINGER.
